UNITED STATES PATENT OFFICE

138,048

DESIGN FOR A FLATIRON OR THE LIKE

Edward J. Fitzgerald, Winsted, Conn., assignor to Son-Chief Electrics, Incorporated, Winsted,
Conn., a corporation of Connecticut

Application November 18, 1943, Serial No. 111,718

Term of patent 14 years

(Cl. D49—6)

To all whom it may concern:

Be it known that I, Edward J. Fitzgerald, a citizen of the United States, residing at Winsted, in the county of Litchfield and State of Connecticut, have invented a new, original, and ornamental Design for a Flatiron or the like, of which the following is a specification, reference being had to the accompanying drawing, forming part thereof, in which:

Fig. 1 is a side elevational view of a flatiron or the like showing my new design;

Fig. 2 is a top plan view thereof; and

Fig. 3 is a front elevational view thereof.

I claim:

The ornamental design for a flatiron or the like, substantially as shown.

EDWARD J. FITZGERALD.
